DOOR HANDLE

Albert L. Birdsall, Grand Rapids, Mich., assignor
to Keeler Brass Company, Grand Rapids, Mich.

Application August 27, 1934, Serial No. 741,543

4 Claims. (Cl. 292—347)

The main objects of this invention are:

First, to provide an improved door handle which is especially well adapted for use with automobile doors and the like, and is very attractive in appearance.

Second, to provide in a door handle of this character an improved assembly which is light in weight yet strong and in which the ferrule is held firmly in place.

Third, to provide an improved escutcheon which is simple and economical in its parts and very attractive in appearance, the arrangement being such that the means securing the escutcheon to the door is concealed.

Objects relating to details and economies of my invention will appear from the description to follow. The invention is defined and pointed out in the claims.

Structures which are preferred embodiments of my invention are illustrated in the accompanying drawing, in which:

Fig. 1 is a view in plan and partially in section of a door handle embodying the features of my invention.

Fig. 2 is an enlarged fragmentary end view of the handle, parts of which are shown in transverse section.

Fig. 3 is a perspective view of the outer escutcheon member.

Fig. 4 is a perspective view of the inner escutcheon member.

Fig. 5 is a perspective view of the ferrule.

Fig. 6 is an enlarged plan view of a modification of the escutcheon, parts being broken away and shown in section.

Referring to the drawing, 1 is a spindle to the outer end of which is rigidly secured the cross bar 2. On the outer side of the cross bar is disposed a hollow support or shell 3 for the finishing cap 4, the latter fitting over the support and cross bar and having an inturned edge flange 5 at the back of the cross bar. The cross bar 2 and the cap support 3 are formed of relatively inexpensive but strong material such as iron, while the cap 4 is formed of relatively thin plated and suitably finished sheet metal which adds to the attractiveness of the assembly.

On the back of the cross bar 2, I dispose a pair of spaced back plates 6 and 7 preferably of the same material as the cap 4, the back plates being arranged at opposite sides of the spindle 1 and having lateral outer edge flanges 8 and 9, respectively, engaged under the inturned end flange 5 of the cap. The inner ends of the back plates are provided with inturned curved flanges 10 and

11 respectively which are spaced from and face the spindle 1.

On the spindle 1, I arrange a tubular ferrule or sleeve 12, preferably of oval or flattened cross section, and preferably formed of the same material and having the same finish as the cap 4 and having a flared outer end 13 engaging the back of the cross bar 2, such flared end being provided with out-turned lateral flanges 14 engaging under the cap flange 5 between and in line with the lateral outer edge flanges 9 of the back plates. At opposite sides of the spindle, I provide the flared end of the ferrule with curved flanges 15 which fit between the inner inturned curved flanges 10 and 11 at the inner ends of the back plates. With this arrangement, the ferrule is held securely in place relative to the other parts of the handle.

In certain types of handles, it is desirable to place the ferrule almost at the end of the handle, in which case the shorter one 6 of the back plates is omitted and an end flange corresponding to the flanges 14 is provided on the ferrule, which is engaged under the inturned flange of the cap. In either case, the ferrule is rigidly fastened into the handle proper, thereby avoiding any tendency for looseness of this part.

I provide the door handle with an improved escutcheon consisting of an inner escutcheon member or support 16 preferably formed of some strong material such as steel, and an outer escutcheon member or cap 17 preferably formed of the same material and having the same finish as the cap 4. The inner escutcheon member is of elliptical shape and is conformed as shown with screw holes 18 and outwardly inclined end flanges 19. The conical central portion 20 of the inner escutcheon member is provided with an inturned flange 21 for coaction with and providing a seat or socket for the inner end of the ferrule or sleeve 12, these parts being urged together by the compression spring 22 arranged around the spindle between the cupped washer 23, the latter being separated from the flange and the abutment lugs 24 on the spindle by the conical washers 25 and 26, respectively.

The outer escutcheon member 17 is adapted to cover the inner escutcheon member and conceal the same and the heads of the securing screws, the outer escutcheon member 17 being conformed to provide a skirt 31 covering and resiliently engaging the flanges 19 of the inner escutcheon member 16 to hold the parts in assembled relation. The outer escutcheon member being made of very light sheet metal rides upon the ferrule of the handle until the inner escutcheon plate has

been screwed to the body, whereupon the outer escutcheon member is snapped into place over the inner escutcheon member. The outer escutcheon member is so shaped that when the skirt 5 31 is compressed at its sides its length increases and it can be readily snapped on or off the inner escutcheon member. When the cap 17 is in place, the support 16 is entirely hidden and the escutcheon becomes a blind escutcheon with no screws 10 or other fastening means showing. The advantages of this are believed to be apparent and include the use of less expensive screws and an attractive appearance of the escutcheon, and the screws are not exposed to invite tampering.

15 In the modified construction of the escutcheon illustrated by Fig. 6 of the drawing, a similar result is obtained through the elasticity or springiness of the metal of the outer escutcheon member. In the modification, the inner escutcheon 20 member 27 has a peripheral flange or keeper 28 which is transversely arched as is the skirt 29 of the outer escutcheon member or cap 30. In this case, the shape of the outside skirt and of the inner escutcheon member are similar, but because 25 of the rounded edge of the cap it will snap over the support which is slightly rounded at its ends, although, of course, the rounded section could be elsewhere or throughout the entire border if desirable. Otherwise, the modification is substantially 30 the same and is used in substantially the same relation as the escutcheon in the foregoing description relative to Figs. 1 to 5, inclusive.

From the foregoing description of my invention taken in connection with the accompanying drawing, it will be appreciated by those skilled in the art that I provide a door handle which is not only very attractive in appearance, but one which is simple and economical in its parts and strong although light in weight. The parts of my assembly 35 are firmly held in place by my arrangement, and this is a very important feature inasmuch as handles of this character are subjected to more or less vibration in use. In addition to the foregoing advantages, my door handle is very effective for the purpose intended and is easy to manipulate, it having a substantially smooth and unbroken grip.

I have illustrated and described my improvements in embodiments which I have found very practical. I have not attempted to illustrate or 50 describe other embodiments or adaptations, as it is believed this disclosure will enable those skilled in the art to embody or adapt my improvements as may be desired.

55 Although I have shown and described certain specific embodiments of my invention, I am fully aware that many modifications thereof are possible. My invention, therefore, is not to be restricted except insofar as is necessitated by the prior art and by the spirit of the appended claims.

Having thus described my invention, what I claim as new and desire to secure by Letters Patent is:

60 1. In a door handle, the combination with a spindle, a cross bar rigidly secured to the end thereof, a cap support disposed on the outer side of said cross bar, and a cap fitting over said sup-

port and cross bar and having an inturned edge flange at the back of said cross bar, of a pair of spaced back plates disposed on the back of said cross bar and at opposite sides of said spindle and having lateral outer edge flanges engaged under the inturned edge flange of said cap and having inner inturned flanges spaced from and facing said spindle, and a tubular ferrule provided with out-turned lateral flanges engaged under said cap flange between and in line with the lateral outer edge flanges of said back plates, the end of the ferrule at opposite sides of the spindle fitting the inner inturned flanges of the back plates, the arrangement being such that the ferrule is held securely in place relative to the other parts of the handle.

2. In a door handle, the combination with a spindle, a cross bar rigidly secured to the end thereof, a cap support disposed on the outer side of said cross bar, and a cap fitting over said support and cross bar and having an inturned edge flange at the back of said cross bar, of a back plate disposed on the back of said cross bar and at one side of said spindle and having a lateral outer edge flange engaged under the inturned edge flange of said cap and having an inner inturned flange spaced from and facing said spindle, and a tubular ferrule provided with out-turned lateral flanges engaged under said cap flange between and in line with the lateral outer edge flange of said back plate, the end of the ferrule at one side of the spindle fitting the inner inturned flange of the back plate, the arrangement being such that the ferrule is held securely in place relative to the other parts of the handle.

3. In a door handle, the combination with a cross bar, and a cap fitting over said cross bar and having an inturned edge flange at the back of said cross bar, of a pair of spaced back plates disposed on the back of said cross bar and at opposite sides of said spindle and having lateral outer edge flanges engaged under the inturned edge flange of said cap and having inner ends spaced from and facing said spindle, and a ferrule engaging the back of said cross bar and provided with out-turned lateral flanges engaged under said cap flange between and in line with the lateral outer edge flange of said back plates, the ferrule at opposite sides of the spindle fitting the inner ends of the back plates, the arrangement being such that the ferrule is held securely in place relative to the other parts of the handle.

4. In a door handle, the combination with a spindle, of a cross bar secured upon the outer end of the spindle, a channeled cap fitted and embracing the edges of said cross bar and having inturned edge flanges at the rear of the cross bar, a back plate disposed on the back of said cross bar and having flanges embraced by the flanges of said cap, and a tubular ferrule embracing said spindle and having out-turned lateral flanges complementing the flanges of said back plate and embraced by the flanges of said cap.

ALBERT L. BIRDSALL.
